UNITED STATES PATENT OFFICE.

PHILIP GEYER, OF NEWARK, NEW JERSEY.

FURNACE.

SPECIFICATION forming part of Letters Patent No. 425,170, dated April 8, 1890.

Application filed August 26, 1889. Serial No. 321,957. (No model.)

To all whom it may concern:

Be it known that I, PHILIP GEYER, of Newark, in the county of Essex and State of New Jersey, have invented a new and useful Improvement in Furnaces, of which the following is a full, clear, and exact description.

My invention relates to an improvement in furnaces, and has for its object to provide a means whereby the products of combustion which are usually permitted to escape are returned over and beneath the grate-bars and the gases contained in said products consumed, thereby greatly economizing in fuel.

A further object of the invention is to provide a means whereby a portion of the waste products of combustion may be returned to the fire and a portion utilized to heat the fresh-air supply for the boiler.

Another object of the invention is to provide a means for heating the fresh-air supply and dampening the products of combustion before they escape through the stand-pipes, whereby the bulk of the products of combustion are rendered heavy and lay in the base-chamber 20 for removal, thereby preventing the marring or disfigurement of the buildings which may be in the vicinity of the boiler.

The object of the invention is also to set the boiler in a substantial and simple manner, the setting being so constructed as to provide flues capable of bringing about the above-named results.

The invention consists in the novel construction and combination of the several parts, as will be hereinafter fully set forth, and pointed out in the claims.

Reference is to be had to the accompanying drawings, forming a part of this specification, in which similar figures of reference indicate corresponding parts in all the views.

Figure 1 is a central vertical section through the boiler and setting, the said section being taken on lines 1 1 of Figs. 2 and 3. Fig. 2 is a horizontal section on line 2 2 of Fig. 1, and Fig. 3 is a vertical transverse section on line 3 3 of Fig. 1. Fig. 4 is a partial longitudinal section through one of the side flues 31, illustrating the application of the damper thereto.

The boiler 10 is supported in the side walls 11^a of masonry, in substantially the usual

manner, and beneath the boiler is a horizontal partition-wall 11, corresponding to the usual base-wall of the boiler-setting, and between the front 12 of the setting and the horizontal wall or partition 11 the grate-bars 13 are supported.

In the rear end wall 14 of the setting, at or about the center, a chimney 15 is supported, which chimney is made to project upward 60 beyond or below the roof of the boiler-house. Between the rear end of the boiler, above the tubes therein and the rear wall, a horizontal wall 16 is constructed, whereby the usual lower fire-flue 17 is obtained and the 65 upper delivery-flue 18, which delivery-flue extends downward in front of the boiler, as best shown in Fig. 1, and at the lower end of the fire-flue 17 a perpendicular transverse wall 19 is constructed of less height than the 70 height of said fire-flue, as is also best illustrated in Fig. 1.

The chimney 15 is provided with a base-chamber 20, covered, preferably, by a metal cap-plate 21, and beneath the horizontal wall 75 11 an air-supply chamber 22 is formed, extending from one side wall to the other, which air-supply chamber connects with the chimney above the plate 21. Near the connection with the air-supply chamber and the chimney 80 in the former an arch 23 is built, containing a central opening 24, the said arch being adapted to support the horizontal wall 11, and in the opening of the arch a fan 25, of any approved construction, is held to revolve, the 85 shaft 26, upon which the fan is secured, being projected through the rear wall of the setting and provided at its outer end with drive-pulleys 27. This air-supply chamber not only connects with the chimney, but also 90 has a direct and uninterrupted communication with the fire-box beneath the grate-bars.

In the chimney a series of perpendicular tubes 28 are grouped, which tubes extend from top to bottom of said end flue, their lower 95 ends extending through the cap-plate 21 into the chamber 20, their upper ends being preferably held in position by an upper cap-plate 29, through which they extend.

Between the upper surface of the chimney 100 and the contiguous face of the upper cap-plate, at the sides and ends of the former,

openings 30 are made in any approved manner, whereby air may enter the chimney and pass downward to the air-supply chamber 22.

- In the side walls 11^a of the setting two 5 downwardly-extending flues 31 and 32 are produced, which flues unite immediately at the rear of the boiler 10, and a communication is established between both of the flues at this point and the boiler delivery-flue 18 by an 10 end flue 33, extending vertically upward from the horizontal wall 16 to the roof of the boiler-setting at the rear of the arch 35, as best shown in Figs. 1 and 3. This flue 33 penetrates the side walls of the setting at the point 15 of junction of the two side flues 31 and 32. From the flue 33 the flues 31 project diagonally downward to the front, and an outlet 34 is provided for these flues 31 over the grate-bars 13, preferably nearer the lower surface 20 of the boiler than the upper face of the grate-bars, as is also best shown in Fig. 1. The side flues 32 extend diagonally downward from the flue 33 and connect with the base-chamber 20 of the chimney—one at each side. 25 Over the top of the boiler, at the rear end, an arch 35 is sprung, provided with a central opening, in which an upper fan 36 is held to revolve, the shaft 37 whereof is carried through the rear wall of the setting and provided with 30 a drive-pulley 38. The fan 36 is thus located at the rear end of the boiler delivery-flue and immediately in front of the flue 33, connecting the opposed side flues 31 and 32.

Into the base-chamber 20 of the chimney 35 one or more pipes 39 are laid, adapted to convey exhaust-steam, when desired, into said chamber, and each of the side flues 31 and 32 is provided with a damper 40, controlled from the outer side of the setting.

- 40 In operation the fan 25 draws the fresh heated air downward through the chimney and forces the said air through the supply-chamber 22 under and through the grate-bars 13 to promote combustion. The products of combustion pass beneath the boiler through the fire-flue 17 into the rear ends of the fire-tubes of the boiler, out through the forward ends of said tubes, and upward in front of and over the boiler through the delivery-flue 18. The fan 36, revolving rapidly in its arch-opening, forces the products of combustion from the delivery-flue into the upper flue 33, connecting the side flues 31 and 32. The said products of combustion now 45 pass down the said side flues 31 and 32, the amount to be passed through each side flue being regulated by the position of the dampers 40. Thus a great amount of the waste products of combustion are returned to the fire-box over the grate-bars through the flues 31, finding an exit at the outlet 34. The remaining portion of the products of combustion, passing down the side flues 32, find an exit into the base-chamber 20 of the chimney, and from thence the said products of combustion pass upward through the tubes 28 out of the chimney, and if exhaust-steam 55

is suffered to enter the chamber 20 it mingles with the ascending products of combustion, dampening the same, and effectually preventing the particles of soot, &c., from defacing surrounding buildings, as, being wet and therefore heavy, they will stay in the base-chamber 20, and if any should go out through the tubes 28 they will fall to the roof of the boiler-house as soon as they are freed from the tube. 70

It will be observed that the ascending waste products of combustion and exhaust-steam effectually heat the tubes 28, and that the air-supply drawn in by the lower fan 25 in its downward passage must pass around and impinge upon these heated tubes, whereby the air-supply for the fire-box is heated to a high degree before being conveyed to 85 the grate-bars.

By reason of the construction above set forth I utilize a maximum amount of the gases contained in the waste products of combustion, which have ordinarily been allowed to escape, and that portion of the waste products of combustion not utilized is made to heat the draft-supply of the boiler. 90

At one side of the boiler-setting, near the rear end, a box-like projection 41 is constructed, provided with a lid and a passage connecting with the chamber 20 at the base of the chimney, as illustrated in Figs. 2 and 3, whereby any sediment formed in the said chamber may be readily extracted through 100 the medium of this box-like projection.

Having thus described my invention, I claim as new and desire to secure by Letters Patent—

1. A boiler-setting provided with a chimney at one end, an air-supply flue connecting the chimney and the fire-box, and side flues connecting the boiler delivery-flue with the fire-box above the grate and the chimney, substantially as shown and described. 105

2. A boiler-setting provided with a chimney at one end, having a base-chamber and tubes extending downward in said base-chamber, an air-supply flue connecting the chimney and the lower portion of the fire-box, and side flues 115 united at their upper ends, connecting the boiler delivery-flue with the fire-box above the grate and the base-chamber of the chimney, substantially as shown and described.

3. A boiler-setting provided with a chimney having a base-chamber and tubes extending from said base-chamber upward, an air-supply flue connecting the chimney and the fire-box beneath the grate, side flues united at their upper ends and provided with dampers connecting the boiler delivery-flue with the fire-box above the grate and the base-chamber of the chimney, a fan held to revolve in the air-supply flue, and a second fan located in the boiler delivery-flue, substantially as and for 120 the purpose specified.

4. The combination, with a boiler, its setting, and the chimney, of an air-supply flue connecting the chimney and the fire-box, a

fan located in the supply-flue near the chimney, a second fan located in the boiler delivery-flue, and a connection, substantially as shown and described, between the boiler delivery-flue at the rear of the fan and the firebox above the grate and said chimney, as and for the purpose specified.

5. The combination, with a boiler and its setting, a chimney having a covered base-chamber, and flues extending through the cover of the chamber upward to the top of said chimney, of an air-supply flue connecting the chimney and the fire-box, a fan located in the air-supply flue near the chimney, a second fan located in the rear end of the boiler delivery-flue, and side flues connected at their upper ends and provided with an upper outlet at the rear of the upper fan, one of said side flues having a connection at its lower end with 10 the fire-box above the grate-bars and the other side flue with the base-chamber of the chimney, all combined to operate substantially as 15 and for the purpose specified.

6. The combination, with a boiler and its setting, a chimney having a covered base-chamber, and flues extending through the cover of the chamber upward to the top of said chimney, of an air-supply flue connecting the chimney and the fire-box, a fan located in the air-supply flue near the chimney, a second 25 fan located in the rear end of the boiler delivery-flue, side flues connected at their upper ends and provided with an upper outlet at the rear of the upper fan, one of said side flues having connection at the lower end with the fire-box above the grate-bars and the other side flue with the base-chamber of the chimney, 30 dampers located in each of the side flues, and an exhaust-steam pipe introduced into the base-chamber of the chimney, substantially as 35 and for the purpose specified.
